UNITED STATES PATENT OFFICE.

OTTO HEINEMANN, OF HORNHAUSEN, GERMANY.

GRAIN-DRILLING MACHINE.

SPECIFICATION forming part of Letters Patent No. 761,885, dated June 7, 1904.

Application filed February 25, 1903. Serial No. 145,002. (No model.)

To all whom it may concern:

Be it known that I, OTTO HEINEMANN, a subject of the King of Prussia, German Emperor, residing at Hornhausen, in the Kingdom of Prussia, German Empire, have invented certain new and useful Improvements in Grain-Drilling Machines, of which the following is a specification.

The lever steering-gear of grain-drilling machines is usually such that it is impossible to set the steering-lever in any desirable position. It has to be held in the hand, therefore, during steering; but this is exceedingly disadvantageous, since shocks and the like cannot properly be controlled, so that it is impossible to prevent the fore carriage at times from leaving the furrow. According to my present invention this inconvenience is entirely overcome.

In the accompanying drawings, Figure 1 is a plan view of the frame of a drilling-machine fitted with my new steering-gear. Fig. 2 is a plan view, and Fig. 3 a longitudinal section, both drawn to an enlarged scale, of the steering-gear itself.

The steering-gear consists of two rods *a b*, connecting the hind and fore carriages. These rods *a b* are pivoted at one end to the hind carriage and are connected at the opposite end to the inner extremities of the double-armed steering-levers *d e*, pivoted at *c c*. The rods *a b* are provided with holes *f* for the purpose of enabling the distance between the axles of the hind and fore wheels to be altered as may be required and to admit of adjustment of the steering-levers.

g h are semicircular toothed racks bolted to the fore frame of the machine, and in these engage the levers *d e*, which are provided with teeth *l* for the purpose. The machine is thus prevented from leaving the furrow unintentionally. The laborer, who holds the reins of the horses in one hand, can with the other hand adjust the lever *d* or *e* by pushing such lever forward or backward (depending upon whether the horses are pulling to the right or left) and setting it. In this manner,

also, stones or the like obstructions in the furrow can be readily avoided.

The steering-lever is conveniently prevented from leaving the peripheral teeth of the semicircular rack by being provided with teeth in the longitudinal direction engaging with the rack-teeth. The detail views, Figs. 2 and 3, clearly illustrate the mechanism. Each rack *g h* is provided with teeth *k* on its periphery, in which engage the three teeth *l* of each lever *d e*. The teeth *l* are not provided directly on the lever itself, but on a block *m*, contained in a case *n* on the under side of the lever. The block is actuated by a spring *o*, which holds the teeth *l* in engagement with the rack-teeth. If the lever is to be disengaged from the rack, this can speedily be done in the well-known manner by means of a hand-lever *p*, pivoted at *q*, and connected to the block *m* by a link *r*.

What I claim as my invention, and desire to secure by Letters Patent, is—

1. A steering-gear for grain-drilling machines, comprising a double-armed toothed steering-lever pivoted to the fore frame and actuating the connecting-bar of the hind and fore carriages, and a curved toothed rack rigidly secured to the fore carriage, the teeth of which rack engage with those of the steering-lever, substantially as described.

2. A steering-gear for grain-drilling machines, comprising a double-armed steering-lever provided with spring-actuated teeth pivoted to the fore frame and actuating the connecting-bar of the hind and fore carriages, and a curved toothed rack rigidly secured to the fore carriage, the teeth of which rack engage with those of the steering-lever, substantially as described.

In testimony whereof I have signed my name to this specification in the presence of two subscribing witnesses.

OTTO HEINEMANN.
